M. S. HANDLER

RAINCOAT

Des. 161,176

Filed Dec. 20, 1948

Fig 3 Maurice S. Handler INVENTOR.
BY Louis Casper

UNITED STATES PATENT OFFICE

161,176

RAINCOAT

Maurice S. Handler, New York, N. Y.

Application December 20, 1948, Serial No. 150,245

Term of patent 3½ years

(Cl. D3—4)

To all whom it may concern:

Be it known that I, Maurice S. Handler, a citizen of the United States, residing in New York city, in the county of New York and State of New York, have invented a new, original, and ornamental Design for a Raincoat, of which the following is a specification, reference being had to the accompanying drawing, forming part thereof.

Fig. 1 is the front view of a raincoat, showing my design.

Fig. 2 is the rear view thereof, and

Fig. 3 is a fragmentary side view thereof.

I claim:

The ornamental design for a raincoat, substantially as shown.

MAURICE S. HANDLER.
